JOSEPH E. PERKINS, OF HARTFORD, CONNECTICUT.

FILING-MACHINE.

1,118,307.

Specification of Letters Patent. Patented Nov. 24, 1914.

Application filed June 12, 1913. Serial No. 773,224.

To all whom it may concern:

Be it known that I, JOSEPH E. PERKINS, a citizen of the United States, residing at Hartford, in the county of Hartford and State of Connecticut, have invented certain new and useful Improvements in Filing Machines, of which the following is a specification.

This invention relates to what I shall for convenience term a "filing machine", one of the primary objects of the invention being to provide substantial and compact means for sustaining a driving shaft and an adjustable tool support which is mounted on said shaft as a center.

Another object is the provision of guide means by which the movement of the tool through a straight path is insured.

Another object is the provision of means by which the work can be accurately and adjustably held with respect to the file or equivalent tool.

The machine possesses other features of novelty and advantage which with the foregoing will be stated at length in the following description wherein I set forth in detail that form of embodiment of the invention which I have selected for illustration in the drawings accompanying and forming part of the present specification, this disclosure being provided to enable those skilled in the art to practice the invention. I do not limit myself to such showing; I may depart therefrom in several respects within the scope of the invention defined by the claims following said description.

Referring to said drawings: Figure 1 is an elevation partly in vertical section and with portions broken away, of a machine involving my invention. Fig. 2 is a transverse section on the line 2—2 of Fig. 1. Fig. 3 is a top plan view of a part of the bed. Fig. 4 is a front elevation of the tool, its carriers and support and certain coöperating devices hereinafter described. Fig. 5 is a transverse section of Fig. 6, the section being taken just back of the screws 22. Fig. 6 is a horizontal section on the line 6—6 of Fig. 4, and, Fig. 7 is a similar view, the section being on the line 7—7 of said Fig. 4.

Like characters refer to like parts throughout the several figures of the drawings, which it will be perceived are on different scales.

The framework for supporting the different parts of the machine may be of any suitable character that shown involving the base or bed 2 and the bearing or upright 3 rising therefrom, the latter being equipped with an overhanging arm 4.

As intimated the machine may be used in various connections, although it is of particular utility when employed for filing, for which reason the title hereinbefore given has been adopted. The file or equivalent tool is given a reciprocatory motion, and any suitable means may be furnished for this purpose, the shaft 5 answering satisfactorily in this connection and being supported at its outer or rear end in a suitable opening in the overhanging arm 4 constituting a convenient bearing member and having a suitable driver such as the band wheel 6 fastened thereto. Said shaft is also shown provided with a balance wheel 7 all as shown best in Fig. 1.

A tool such as the file 8 is sustained but not directly, by a support which may be of any suitable kind, the disk-like bracket or circular plate 9 being shown for this purpose, said disk or bracket 9 having upon its inner side the hollow hub or tubular pivot 10 which fits and turns within the opening 11 at the outer end of the arm 4, this hub 10 presenting the outer support for the shaft 5, the enlarged cylindrical portion 12 of which is rotatively disposed within said hub or tubular hub 10, the bushing 13 (Fig. 1) being interposed between said enlargement 12 and hub 10. The arm 4 is provided at its outer end with an annular flange 14 against which the disk or bracket 9 fits flatwise, the flange and disk being approximately of equal diameter. This provides a substantial bearing for the disk 9 transverse to its axis of oscillation, said disk rocking when being adjusted, on the shaft 5 as a pivot and also in the arm 4 when the stud 10 also acts as a pivot. The bracket 9, therefore, has a double bearing, and it in turn sustains the shaft 5, so that no independent bearing is necessary in this particular connection.

The turning of the bracket 9 is to effect the angular adjustment of the file or equivalent tool 8, there being two carriers in conjunction with said file, a main carrier as 15, and an auxiliary carrier or holder as 16 to which latter the file 8 as will hereinafter appear, is directly connected. The main car-

rier 15 is reciprocatory, or slideable radially of the disk 9, receiving its motion in some suitable manner, as will hereinafter appear from the shaft 5 to thereby move the file 8 up and down. The disk 9 is equipped with 5 outward extensions or lugs 17 approximately diametrically opposite each other, which receive the reciprocatory main carrier 15 made substantially in the form of a slide 10 square in cross section, longitudinal adjustments of the file being accomplished by the endwise adjustment of the auxiliary carrier 16, the main carrier 15 having an opening 15 its entire length to slidably receive said auxiliary carrier or tool holder 16. The auxiliary carrier 16 is grooved as at 18 at 20 its lower end to receive the tang of the file 8 which is rigidly held in said groove 18 by the clamping member 19, said carrier 16 being maintained in a longitudinally adjusted position by a set screw 20 adapted to engage the same said screw being tapped through the main carrier 15.

The circular flange 14 is shown having 25 two arcuate slots 21 struck from the axis of rotation of the shaft 5, the screws 22 extending through said slots and being tapped into the support or disk 9, the heads of said screws being adapted to engage 30 against said flange to hold the support in an adjusted position. By loosening the screws the support can be turned so as to vary the angle of presentation of the file or other tool to the work. When the adjustment is 35 secured the two screws are set and will maintain the adjustment.

The shaft 5 is shown (Figs. 1 and 6) provided with a head 23 (shown as a disk) at its outer end, disposed in the substantially central counterbore 24 of the adjustable support 9, said head having an adjustable connection, for example through a stud hereinafter described, with the main carrier 15, so that the length of stroke of 40 said carrier and therefore of the tool 8 connected therewith can be regulated. Said carrier 15 as illustrated, has a transverse slot 25 (Figs. 1, 4 and 6) to receive the anti-friction roller 26, the pivot 27 of which consists of a screw tapped into the tee block 28 45 slideable in a radial tee slot 29 which extends outward from a point intersected by the axis of rotation of the shaft 5, by reason of which said block, on loosening the screw 27, can be adjusted toward and from said axis. When the axes of the screw 27 and shaft 5 50 are coincident, the carrier 15 will not be reciprocated but by moving the screw 27 and therefore the anti-friction roller 26 55 away from the axis of rotation of the shaft, the carrier 15 can be reciprocated as the shaft turns, the greater the distance of the anti-friction roller and screw from the axis of rotation of the shaft 5, the greater the 60 stroke of the carrier 15. When the adjust- 65

ment of the anti-friction roller is accomplished the screw 27 will be set.

There are two guides for the file 8, one connected with the support 9 and the other mounted independently of said support but 70 adjustable to conform to the position of the guide on the support. The guide connected with the support 9 is denoted in a general way by 30, and it consists of an elongated bar 75 preferably longitudinally adjustable as will hereinafter appear, the lower portion of the guide or base being curved inward and the active portion of said guide being provided with an anti-friction roller or guiding member 31 supported at the lower end of said 80 bar and adapted to be engaged by the file as the same reciprocates during work. As a convenient means for effecting the longitudinal adjustment of the guide or bar 30 the same may be provided with longitudinal, 85 superposed slots 32 through which extend the shanks of binding screws 33 tapped into the extensions 17. By loosening the binding screws the guide 30 may be longitudinally adjusted and when the adjustment is 90 secured the binding screws will be set. The second guide is designated by 34, and it is shown as consisting of a slide fitting a chamfered groove or channel 35 extending entirely across the upper surface of the base, 95 bed or table 2. The active portion of the guide 34 consists of an anti-friction roller 36 supported at the inner end of the said slide 34 adjustable by a screw 37 tapped into the pendent projection 38 thereof and carried by a bearing 39 on the bed 2. Through the operation of the screw 37, the slide may be moved in and out, so that the anti-friction roller 36 can be adjusted to a position 100 to correspond with that of the cooperating anti-friction roller 31 whereby during filing or other work the file or equivalent tool 8 will simultaneously engage both anti-friction 105 rollers or active portions of the two guide members to prevent flexing or bending of the file and thus insure accurate work. The bed 2 has a slot 40 constituting a continuation of the groove 35 through which the file moves during its reciprocation. 110

The groove 35 receives a second slide 42 115 to which is connected a micrometer adjusting screw 43 supported by the bed 2 and by which fine adjustments of the slide and therefore of the gage member 44 supported thereon are possible, rough adjustments being effected by the shifting of the gage member on the slide 42. The gage member 44 is shown as consisting of a segmental plate having a straight flange 45 at its inner 120 edge against which the work is placed, the work at such time resting on the slide 42. As will hereinafter appear the gage or abutment 44 is adjustable about an axis to effect 125 variations in the angle of presentation of the work to the file 8. As represented the 130

gage member or abutment 44 is pivotally mounted, it being connected through the pivot 46 with the slide, the slide having a row of threaded perforations 47 to interchangeably receive the pivot (shown as a screw) to thereby provide for the adjustment of said gage member or abutment 44 longitudinally of the slide or block 42. To maintain the angular adjustment of the gage member 44, the binding screw 48 may be provided, said binding screw being adapted to interchangeably fit any one of said tapped holes or perforations 47, said screw extending through the arcuate slot 50 struck from the center of movement of the segment or plate 44.

What I claim is:

1. In a machine of the class described the combination of a support adjustable about an axis, a reciprocatory tool carrier on said support, a guide for the tool normally rigidly connected with said support, and a second guide for the tool mounted independently of the support and adjustable to conform to the position of the guide on the support on the adjustment of said support.
2. In a machine of the class described,

the combination of a support adjustable about an axis, a reciprocatory tool carrier on said support, a guide normally rigidly connected with said support and the active portion of which consists of an anti-friction roller, and an adjustable slide, sustained independently of said support and also constituting a guide, the active portion of the slide consisting of an anti-friction roller.

3. In a machine of the class described, the combination of a bearing, a support having a counterbore and having an inwardly extending hollow pivot, the hollow of which opens into said counterbore, the pivot being supported by the bearing to provide for the angular adjustment of said support, a tool carrying slide on said support, a shaft extending through the hollow pivot and into said counterbore, the shaft being also sustained by said bearing, and having a head in said counterbore and means connected with said head for reciprocating said slide.

In testimony whereof I affix my signature in presence of two witnesses.

JOSEPH E. PERKINS.
